SUSPENSORY GARMENT

Thomas La Maida, University Heights, Ohio

Application November 15, 1937, Serial No. 174,538

3 Claims. (Cl. 128—159)

This invention relates to improvements in wearing apparel or garments, and more particularly, to personal wear garments individually adaptable for use by men. In a general way, this 5 invention relates to the type of combination suspensory garments disclosed in United States Letters Patent No. 1,985,507 issued to me on December 25, 1934.

I have discovered, that by reconstructing the 10 article disclosed in the above patent, to include certain new features, that certain new and useful improvements are presented over the above patent, as hereinafter disclosed.

Therefore, objects of my present invention are, 15 to provide a suspensory garment characterized by the advantages of simplicity and low cost of construction, and providing a scientifically designed garment for men, affording the maximum comfort and ease and support in wearing, and inhibiting creeping or binding of the garment on the wearer.

Another object is to provide a construction of the class described, which is snug fitting and comfortable under all conditions and may be embodied in various forms.

Another object is to provide a suspensory which is comfortable and effective during all physical activities of the wearer.

Other and further objects of my invention will 30 appear during the course of the following description.

In the accompanying drawing forming a part of this specification:

Fig. 1 is a plan view of the blanks from which 35 my invention is assembled,

Fig. 2 illustrates a partial assembly of the blanks, shown in Fig. 1,

Fig. 3 is a front view of the assembled garment,

Fig. 4 is a rear view of the assembled garment, 40 while

Fig. 5 is a side view of the assembled garment.

The garment disclosed herein is adapted to be manufactured from any suitable material, the blanks from which it is assembled being laid out 45 in Fig. 1, wherein the numeral 11 represents front crotch members having cooperating inner longitudinal edge portions *a—a*, adapted to be overlapped and sewn together as shown in Fig. 2, outer longitudinal edge portions *b—b*, upper transverse edge portions *c—c*, and lower convex edge portions *d—d*.

Abdominal engaging members 12, adapted to be disposed around the abdomen of the wearer, are provided with curved edge portions *e—e*, inner 50 vertical edges *f—f*, outer vertical edges *g—g*, low-

er leg encircling edges *h—h*, while top edges *i—i* are cut out to form notches 13 adapted to be formed into pleats in the finished garment.

Rear crotch members 14, forming a part of the back portion of the completed garment, are provided with cooperating inner longitudinal edge portions *j—j*, curved outer edges *k—k*, lower outer edge portions *L—L*, lower edge portions *m—m*, while the upper ends are cut to form tabs 15 having convex forward edges.

In assembling the blanks, above illustrated, into a finished garment the tabs 15, shown at the upper end of the rear crotch members 14 in Fig. 1, are united to the lower edge portions *d—d* of the front crotch members 11 as shown in Fig. 2, 15 the inner longitudinal edge portions *j—j* of the rear crotch members 14 and a part of the inner longitudinal edge portions *a—a* of front crotch members 11 being first united. The two rear crotch members 14 are preferably bias cut, in 20 order to provide sufficient stretching of the material to allow compensative yielding in conformity to active body movements, thus providing great comfort for the wearer at these parts, which form a protruding pouch 16, shown in 25 Figs. 3 and 5, constituting a suspensory means.

The abdominal engaging members 12 are then assembled to the crotch parts, above described, in such a manner that the outer edge portions *L—L* of the rear crotch members 14 engage the edges 30 *g—g* of the abdominal encircling members 12, as shown in Fig. 4 with the leg encircling edges *h—h* doubled back and united to the lower part of the edges *g—g*, while outer edge portions *b—b* of front crotch members 11 are united to curved 35 edge portions *e—e* of abdominal engaging members, as shown in Fig. 3. If desired a top belt means 17, having the top edges of front crotch member 11, rear crotch members 14, and abdominal encircling members 12 united thereto, 40 may be provided, while ties 18, fastened to the belt means 17 permit the garment to be taken in at the waistline and tied around the loins of the wearer, in order to provide uplifting action for the suspensory feature of the garment. The 45 notches 13 at the top of the abdominal encircling members 12 permit the material to be formed into pleats 19, permitting the garment to conform to the contour of the wearer's body.

The garment above described, thus provides a 50 comfortable pouch 16 adapted to conform to the contour of a male wearer, the amount of uplifting or suspensory effect being controlled by regulating the position and tension of the garment on the wearer by means of the ties 18. By elimi- 55

nating cross ties between the front and rear crotch members, as provided in this construction, greater comfort and utility are achieved due to the elimination of such ties which frequently 5 cause chafing, irritation and discomfort, at the same time this construction permits the manufacturing of such garment at a cost relatively much lower, than the cost of a garment having a cross tie, due to the saving of time and material. 10 The garment, herein illustrated, may be manufactured of various materials, and it may be found desirable to make the entire garment from the conventional materials, thus providing a neat and attractive garment. The position and arrangement of the pouch 16 provides yielding compensating support where desired, and prevents slacking and lack of protection and support otherwise.

It will be apparent to those skilled in the art 20 that the invention disclosed herein may be variously changed, used or modified, without departing from the spirit of the invention or sacrificing the advantages thereof, and that the embodiment of my invention, herein disclosed, is illustrative 25 and that my invention is not limited thereto.

I claim:

1. A bifurcated suspensory garment comprising a pair of front crotch members, a pair of rear crotch members, and a pair of abdominal members for encircling the legs and covering the abdomen of the wearer, the pair of front crotch members having inner longitudinal edges which are secured together for a portion of their lengths at the lower portions thereof, the rear crotch members being secured together throughout their inner edges and having constricted intermediate sections and tab portions at their front ends, which tab portions are secured to the lower adjacent edges of the front crotch members, the position and arrangement of the cooperating front crotch members and rear crotch member tab portions providing a suspensory pouch for the wearer, the abdominal members being provided with lower portions of sufficient length to encircle 30 a leg of the wearer and having the inner edges of such portions secured to the lower part of the outer edges of the respective abdominal members for that purpose, the upper parts of the said last-mentioned outer edges being secured to respectively adjacent outer edge portions of the rear crotch members, and said abdominal members having their inner edges cut diagonally to provide upwardly tapering portions which are secured at their inner edges to the outer edges of the front crotch members and the remaining portions of the outer edges of the rear crotch members, whereby adjustment of the upper edge or waistline of the completed garment will control the supporting effect of the pouch.
2. A bifurcated suspensory garment comprising a pair of front crotch members, a pair of bias cut rear crotch members, and a pair of abdominal members for encircling the legs and covering the

abdomen of the wearer, the pair of front crotch members having inner longitudinal edges which are secured together for a portion of their lengths at the lower portions thereof, the rear crotch members being secured together throughout their inner edges and having constricted intermediate sections and tab portions at their front ends, which tab portions are secured to the lower adjacent edges of the front crotch members, the position and arrangement of the cooperating front crotch members and rear crotch member tab portions providing a suspensory pouch for the wearer, the abdominal members being provided with lower portions of sufficient length to encircle a leg of the wearer and having the inner edges of such portions secured to the lower part of the outer edges of the respective abdominal members for that purpose, the upper parts of the said last-mentioned outer edges being secured to respectively adjacent outer edge portions of the rear crotch members, and said abdominal members having their inner edges cut diagonally to provide upwardly tapering portions which are secured at their inner edges to the outer edges of the front crotch members and the remaining portions of the outer edges of the rear crotch members, whereby adjustment of the upper edge or waistline of the completed garment will control the supporting effect of the pouch.

3. A bifurcated suspensory garment comprising a pair of front crotch members, a pair of rear crotch members, and a pair of abdominal members for encircling the legs and covering the abdomen of the wearer, the pair of front crotch members having inner longitudinal edges which are secured together for a portion of their lengths at the lower portions thereof, the rear crotch members being secured together throughout their inner edges and having constricted intermediate sections and tab portions at their front ends, which tab portions are secured to the lower adjacent edges of the front crotch members, the position and arrangement of the cooperating front crotch members and rear crotch member tab portions providing a suspensory pouch for the wearer, the abdominal members being provided with lower portions of sufficient length to encircle a leg of the wearer and having the inner edges of such portions secured to the lower part of the outer edges of the respective abdominal members for that purpose, the upper parts of the said last-mentioned outer edges being secured to respectively adjacent outer edge portions of the rear crotch members, and said abdominal members having their inner edges cut diagonally to provide upwardly tapering portions which are secured at their inner edges to the outer edges of the front crotch members and the remaining portions of the outer edges of the rear crotch members, and means for adjusting the length of the upper edge or waistline of the garment to control the supporting effect of the pouch.

THOMAS LA MAIDA.
